(21) Appl. No.: **29/410,616**

Primary Examiner — Sandra Morris

(22) Filed: **Jan. 10, 2012**

(74) *Attorney, Agent, or Firm* — Adam K. Sacharoff

(51) LOC (9) Cl. **21-01**

CLAIM

(52) U.S. Cl. **D21/578**

The ornamental design for a robotic toy having a triangular top, as shown and described.

(58) Field of Classification Search D6/598; D11/158; D21/576–578, 585–588, 623, D21/630, 620, 658–661; D30/160; 446/3, 446/72, 97–98, 268–269, 351, 484

DESCRIPTION

See application file for complete search history.

FIG. 1 is a top perspective view showing a first embodiment of the robotic toy having a triangular top;
FIG. 2 is a left side view of FIG. 1;
FIG. 3 is a right side view of FIG. 1;
FIG. 4 is a front side view of FIG. 1;
FIG. 5 is a back side view of FIG. 1;
FIG. 6 is a top side view of FIG. 1;
FIG. 7 is a bottom side view of FIG. 1;
FIG. 8 is a bottom back side perspective view of FIG. 1;
FIG. 9 is a top perspective view showing a second embodiment of the robotic toy having a triangular top;
FIG. 10 is a left side view of FIG. 9;
FIG. 11 is a right side view of FIG. 9;
FIG. 12 is a front side view of FIG. 9;
FIG. 13 is a back side view of FIG. 9;
FIG. 14 is a top side view of FIG. 9;
FIG. 15 is a bottom side view of FIGS. 9; and,
FIG. 16 is a bottom back side perspective view of FIG. 9.
